UNITED STATES PATENT OFFICE.

EVARICE LADOUCEUR AND NAPOLEON E. H. FERLAND, OF MANCHESTER,
NEW HAMPSHIRE.

DESIGN FOR A SINK-SCRAPER.

SPECIFICATION forming part of Design No. 31,936, dated December 5, 1899.

Application filed November 3, 1899. Serial No. 735,732. Term of patent 3¹ years.

To all whom it may concern:

Be it known that we, EVARICE LADOUCEUR, a subject of the Queen of Great Britain, and NAPOLEON E. H. FERLAND, a citizen of the 5 United States, both residing at Manchester, in the county of Hillsborough and State of New Hampshire, have invented and produced a new and original Design for Kettle and Sink Scrapers, of which the following is a specification, reference being had to the accompanying drawing, forming a part thereof.

The leading feature of our design is the peculiar form given the working edge and the ends of our sink-scraper, as clearly illustrated 15 in the drawing, a perspective view, accompanying and forming a part of this specification.

Referring to the drawing, A represents the blade of the implement or scraper, which is made substantially flat from end to end, one 20 of its ends a being quite wide and formed at an acute angle with the top and bottom, said top and bottom terminating at the opposite end in a rounded point a'.

The form given the top is of minor import-

tance; but the bottom a² should be both 25 curved and flat, causing it to somewhat resemble a sled-runner, the curved portion terminating in the rounded point a' and the flat portion terminating in a sharp point by its union with the angular end a. 30

The blade or scraper A is secured to a rod B, which terminates in a wooden handle C, curved and ornamented, as shown, and said blade will have its working edge a² ground on one side, giving said edge a beveled appearance. 35

Having described our invention, what we claim as new, and desire to secure by Letters Patent, is—

The design for a sink scraper, as herein shown and described. 40

In testimony whereof we affix our signatures in presence of two witnesses.

EVARICE LADOUCEUR.

NAPOLEON E. H. FERLAND.
